UNITED STATES PATENT OFFICE.

JOSEPH J. FISCHER, OF BELLEPLAINE, MINNESOTA.

ELEVATOR.

No. 833,032.

Specification of Letters Patent.

Patented Oct. 9, 1906.

Application filed May 8, 1906. Serial No. 315,817.

To all whom it may concern:

Be it known that I, JOSEPH J. FISCHER, a citizen of the United States, residing at Belleplaine, in the county of Scott and State 5 of Minnesota, have invented a new and useful Elevator, of which the following is a specification.

This invention relates to elevators; and its object is to provide a device of this character 10 adapted to be used upon stairways for the purpose of lowering barrels and other heavy 15 articles into cellars, &c.

A still further object is to provide an elevator which may be portable and can be 15 utilized for unloading railway-cars and for various other purposes.

A still further object is to provide means whereby the operation of the elevator can be under the direct control of the operator, so 20 that the speed of the descent of the carriage can be regulated and said carriage can be brought to a quick stop, if desired.

A still further object is the provision of an elevator which will not interfere with the use 25 of the steps to which it is connected.

With the above and other objects in view the invention consists of guide-rails, between which are mounted runners which support a carriage shaped to hold articles placed thereon, said carriage being also formed with a platform on which the operator may ride, if desired. The carriage is connected to endless chains or belts, which are mounted on sprockets or pulleys disposed adjacent the 30 ends of the rails, and the rotation of these devices is controlled by a weight or spring, which is adapted to hold the carriage normally in position at the upper ends of the rails. Said springs or weights, however, 35 will be overbalanced by any articles placed upon the carriage, and by loading the carriage the same will move downward automatically and tension the springs or raise the weight, and after the carriage has been unloaded upon reaching its lowered position the springs or weights will return it to its initial position to receive another load. A 40 brake of novel form is provided for regulating the movement of the carriage.

50 The invention also consists of certain other novel features of construction and combinations of parts, which will be hereinafter more fully described, and pointed out in the claims.

In the accompanying drawings is shown the preferred form of the invention.

In said drawings, Figure 1 is a side eleva-

tion of the device, a portion of one of the rails being broken away to show the carriage in end elevation, said carriage being shown partly lowered. Fig. 2 is an elevation of the 6c other side of the device, a portion thereof being broken away to show the supporting means in section. Fig. 3 is a plan view. Fig. 4 is a transverse section through a part of the device and showing the adjustable 65 supporting-yoke. Fig. 5 is a side elevation of the lower portion of the device, the same being provided with modified carriage-actuating means; and Fig. 6 is a longitudinal section through the lower portion of another 70 modified form of device.

Referring to the figures by characters of reference, 1 are side beams, between which are disposed steps 2, and a cross-strip 3 connects the side beams at a point adjacent their 75 centers and has a rotatable screw-threaded stem 4 swiveled therein and threaded into a yoke 5, which is supported by an axle 6, having wheels 7 thereon. Braces 8 connect the side beams with the axle, so as to form, with 80 the yoke, a rigid but adjustable support for the device. Rollers 9 are mounted in the lower ends of the side beams and operate, in conjunction with the wheels 7, to facilitate the movement of the elevator from place to 85 place.

A shaft 10 is journaled within the lower ends of the side beams, and secured to this shaft close to the inner face of each of said beams is a sprocket 11. A disk 12 is secured 90 to the shaft near one end thereof, and adjacent the outer face of one of the beams 1 and rotatable with this disk is a toothed wheel 13, adapted to be engaged by a finger 14, extending from a lever 15. A spring 16 is connected to this lever and to one of the side beams for the purpose of holding the finger 95 normally projected into the path of the wheel 13. A brake-shoe 17 is formed at one end of the lever and is adapted to be swung into contact with the periphery of the disk 12. An actuating-lever 18 is fulcrumed adjacent the upper end of one of the beams 1 and is connected, by means of a rod or cable 19, with the lever 15, and by swinging the lever 18 in 100 one direction the finger 14 can be swung out of the path of the wheel 13, and by continuing the movement of said lever 18 the shoe 17 can be pressed into contact with the periphery 105 of the disk 12. A spring 20 is coiled about and secured to one end of the shaft 10, and its other end is secured to a fixed part of the ele-

vator, and this spring serves to control the rotation of the shaft.

Extending around each sprocket 11 is an endless chain 21, which passes over a sprocket 5-22, journaled upon a stud 23, extending inward from the upper portion of the device. In order that all portions of the chain may be held out of contact with the steps, an idler 24 is mounted on the side beam adjacent the 10 lower sprocket 11 and constitutes a support for the chain. This side beam has oppositely-disposed inverted-L-shaped rails 25 fastened to it and forming a slot between their adjoining edges, into which extend runners 26, the 15 lower faces of which are rounded and recessed, so as to reduce friction to the minimum. The runners are secured to the ends of a carriage 27, having an extension 28 extending from its lower edge and supported by 20 braces 29 at the ends thereof, said extension being provided with arms 30. A rearward extension 31 projects from the upper or rear edge of the carriage at the center thereof and constitutes a platform on which an operator 25 may stand, if desired. The chains 21 can be tightened in any desired manner. The lower ends of the rails 25 are curved downward, so that when the carriage assumes a position thereabove it will be tilted, so as to 30 dump therefrom any articles which may be mounted thereon. The lowest step 34 of the flight is hinged, so that it can be swung upward in order to expose the shaft 10.

Spring 20 is of sufficient strength to hold 35 the carriage normally in position upon the upper ends of the rails, and the support of the carriage is adapted to be adjusted so as to bring the upper step of the flight at a proper height to receive the articles to be conveyed 40 downward. Finger 14 normally locks the carriage against downward movement, because the shaft 10 cannot rotate, and it is therefore possible to load heavy articles, such as barrels, upon the carriage. When it is desired 45 to lower said articles, the lever 18 is pulled backward, so as to withdraw the finger from the path of the wheel 13, and the weight of the articles on the platform will cause said carriage to slide downward on the rails and 50 tension spring 20. The downward movement of the platform can be regulated by swinging the shoe 17 against the periphery of disk 12. When the carriage reaches the lower ends of rails, it will tilt thereon and discharge the articles mounted on the carriage.

As soon as these articles are discharged the spring 20, which is tensioned by the downward movement of the carriage, will return the parts to their original position. Should 60 the articles on the carriage be too light to cause the proper actuation of said carriage, the operator can stand on the rearward extension 31, so that his weight will be added and the proper movement insured.

65 Instead of using a spring 20 for returning

the carriage after its contents have been discharged a standard 35 may be secured to one of the beams 1 and provided with a pulley 36, on which a cable 37 may be placed. This cable is adapted to wind on a drum 38, secured to shaft 10, and has a weight 39 at its free end, which has the same effect as the spring.

If desired, the entire elevator can be built upon a fixed stairway, in which event the 75 construction would be similar to that shown and described, with the exception of course that the strip 3, stem 4, and yoke 5, together with the parts connected thereto, would be dispensed with. Where the elevator is connected in this manner a weighted cable 40 can be connected to a drum 41, secured to the shaft 10 directly under the lower step 34, and said step can be swung upward on its 80 hinges, so that access can be readily had to the cable. It will of course be necessary to provide a hole under the stairs in which the weighted cable 40 will hang, although, if desired, a cable could be extended over a pulley 85 supported above the carrier in any preferred 90 manner.

It will be obvious that the elevator herein described will be of considerable utility in lowering barrels or boxes, &c., into cellars, and by making it portable it will be found 95 very desirable in unloading trunks and other articles from railway-cars at stations in rural districts. A grip 42 is preferably slidably mounted on the cable 19 and is adapted to be grasped by the operator if he is moving 100 downward with the carriage, so that the movement of said carriage can be kept under control by him.

The preferred form of the invention has been set forth in the foregoing description; 105 but I do not limit myself thereto, as I am aware that modifications may be made therein without departing from the spirit or sacrificing the advantages thereof, and I therefore reserve the right to make such changes 110 as fairly fall within the scope of the invention.

What is claimed is—

1. A carrier comprising connected side beams, rails upon said beams and having downwardly-turned ends, a carriage slidably mounted between the rails, and resilient means for holding the carriage normally in position upon the upper portions of the rails.
2. In an elevator the combination with inclined side beams; of a carriage mounted upon and adapted to move longitudinally of the side beams, a spring-controlled shaft journaled within the beams, and flexible connections between the shaft and the carriage, said carriage being held normally in position at 125 the upper end of the side beams.
3. In a carrier the combination with inclined side rails; of a carriage movably mounted thereon adapted to travel longitudinally thereof, a shaft journaled within the beams, 130

endless flexible connections between the shaft and carriage, and means connected to the shaft for automatically moving the carriage from the lower to the upper end of the beams.

5 4. In a carrier the combination with side beams having rails mounted thereon; of a carriage guided by said rails and upon the beams, a shaft journaled within the beams, flexible connections between the shaft and the carriage, means for automatically actuating the shaft to return the carriage to raised position after it has been lowered, and means for controlling the rotation of the shaft.

15 5. In a carrier the combination with side beams having rails mounted thereon; of a carriage guided by said rails and upon the beams, a shaft journaled within the beams, flexible connections between the shaft and the carriage, means for automatically actuating the shaft to return the carriage to raised position after it has been lowered, and means for controlling the rotation of the shaft.

20 6. In a carrier the combination with side beams having guide-rails thereon; of a carriage mounted upon the beam and guided by the rails, a shaft journaled within the beams, sprockets carried thereby, endless chains mounted on the sprockets and connected to the carriage, idlers engaging the chains, means connected to the shaft for automatically rotating it to move the carriage to one

25 end of the beams, and means for controlling the rotation of the shaft in either direction.

7. A carrier comprising side beams, steps

interposed therebetween, a carriage movably mounted on the beams, a shaft journaled within the beams, means movable with the shaft for actuating the carriage, means connected to the shaft for automatically rotating the same in one direction, and means for controlling the rotation of the shaft.

8. A portable carrier comprising connected side beams, an adjustable support therefor, wheels carried by the supporting-beams, a shaft journaled within the side beams, a carriage mounted on said beams, flexible connections between the shaft and carrier for transmitting motion to the carriage from either direction, and means connected to the shaft for automatically moving the carriage upward when in lowered position.

9. A portable carrier comprising connected side beams, an adjustable support therefor, wheels carried by the supporting-beams, a shaft journaled within the side beams, a carriage mounted on said beams, flexible connections between the shaft and carriage for transmitting motion to the carriage from either direction, means connected to the shaft for automatically moving the carriage upward when in lowered position, and manually-operated means for controlling the rotation of the shaft.

In testimony that I claim the foregoing as my own I have hereto affixed my signature in the presence of two witnesses.

JOSEPH J. FISCHER.
